UNITED STATES PATENT OFFICE.

MILLARD F. SMITH, OF PHILADELPHIA, PENNSYLVANIA.

SHIELD FOR BEARING-BARS OF PAINTERS' SCAFFOLDS.

SPECIFICATION forming part of Letters Patent No. 363,179, dated May 17, 1887.

Application filed March 8, 1887. Serial No. 230,082. (No model.)

To all whom it may concern:

Be it known that I, MILLARD F. SMITH, a citizen of the United States, and a resident of Philadelphia, Pennsylvania, have invented 5 certain Improvements in Shields for Bearing-Bars of Painters' Scaffolds, of which the following is a specification.

The object of my invention is to provide an effective means whereby the bearing-bar of a painter's scaffold is prevented from abrading or otherwise marring the surface of a wall in front of which the scaffold is hung, and this object I attain in the manner which I will now proceed to describe, reference being had to the 15 accompanying drawings, in which—

Figure 1 shows a painter's scaffold the bearing-bars of which are provided with shields or guards constructed in accordance with my invention, Fig. 2 being a perspective view, on a 2c larger scale, of one of the bearing-bars and its shield; and Fig. 3, a transverse section of the same as applied to the scaffold.

A represents the frame of the scaffold, which is constructed in the usual manner, and has 25 near each end a yoke, a, which is hung by means of suitable tackle to the curved suspension-hooks b, which bear upon the roof or other available portion of a building in front of which the scaffold is to be suspended.

3c Near each end of the scaffold is a bar, B, which projects inward beyond the scaffold, the inner ends of these bars usually bearing against the wall of the building, so that said bars serve to maintain the scaffold at its proper distance 35 from such wall. The lateral and vertical swaying of the scaffold, however, causes the inner ends of the bearing-bars to move about over the surface of the wall and to scratch, abrade, or otherwise mar the same, and this objection

40 is only in a measure overcome by providing the inner or bearing ends of the bars with pads, cushions, rubber rollers, or equivalent devices. In carrying out my invention, therefore, I discard the usual expedient of a pad or equivalent device moving with the bar and employ a shield or guard, the normal position of which on the wall is fixed, the inner end of the bearing-bar moving over the surface of this shield as the scaffold sways or tilts.

50 Each shield consists in the present instance of a plate, D, of any suitable material, preferably metal, this plate being provided on that

side adjacent to the wall with a facing or coating of felt, rubber, leather, cloth, cork, or equivalent material which will present a good 55 frictional surface. Each shield is hung by means of springs d from the outer ends of arms E, which are mounted upon the top of the bearing-bar and suitably braced, so that their outer ends are at a proper height above the shield, 60 the latter being so supported that the outer end of the bearing-bar will under ordinary circumstances occupy a position about the center of the shield.

The bar B has near its outer end laterally-projecting arms G, the outer end of each of which is connected by means of springs f to the adjacent upper and lower corners of the shield. The arms F thus serve to support the shield in its proper vertical relation to the bearing-bar B, 7c while the arms G serve to retain the shield in its proper lateral or sidewise position in respect to said bar. The pressure of the bar against the shield causes such a frictional hold of the padded face of said shield upon the wall 75 that any lateral or vertical movement of the bearing-bar will not cause a like movement of the shield, but will simply cause the stretching of one or more of the spring-connections between the shield and its supporting-arms, 80 said shield remaining stationary and the end of the bar traveling over the face of the same; hence it will be evident that there can be no such scratching or marring of the surface of the wall as might be caused by a pad or cushion traveling with the bearing-bar. 85

The bearing-bars B are secured to the frame of the scaffold by means of screw-clamps g, the stems of which are adapted to slots i in the bearing-bars, so that the bars can be adjusted 8c in respect to the scaffold so as to project to any desired extent inward from the scaffold, and thus hold the latter at any required distance from the face of the wall.

Spring-connections between the arms F and G and the shield will not be necessary if said arms themselves possess a proper amount of elasticity, and the arms G and their connections may even be dispensed with in some cases, although their use is preferred, as tending to 95 aid in preserving the proper relation between the shield and bearing-bar. A single arm, F, might also, if desired, be used in place of the two arms shown, this arm having a single con-

- nection with the center of the shield at the top; or two connections leading to the opposite upper corners of the shield, as desired, the construction shown, however, being preferred.
- 5 I claim as my invention--
1. The combination of the bearing-bar of a painter's scaffold, a shield for the end of the same, and an elastic support for said shield carried by the bar, all substantially as specified.
- 10 2. The combination of the bearing-bar of a painter's scaffold, a shield therefor having a frictional face for bearing against the wall, and an elastic support for said shield carried by the bar, all substantially as specified.
- 15 3. The combination of the bearing-bar of a painter's scaffold, a loose shield at the inner end of the same, an arm projecting above the bar, and a connection between the end of said arm and the shield, all substantially as specified.
- 20
4. The combination of the bearing-bar of a painter's scaffold, a loose shield at the inner end of the same, one or more arms projecting above the bar, arms projecting laterally beyond the bar, and a connection between the end of each of said arms and the shield, all substantially as specified.
5. The combination of the bearing-bar of a painter's scaffold, one or more arms projecting above the same, laterally-projecting arms on the bar, and a spring interposed between the end of each of said arms and the shield, all substantially as specified.

In testimony whereof I have signed my name to this specification in the presence of two subscribing witnesses.

MILLARD F. SMITH.
